(57) **CLAIM**

The ornamental design for a portable enclosure for an electric scooter, as shown and described.

DESCRIPTION

FIG. 1 is a perspective view of a portable enclosure for an electric scooter with the front flap in an open position.

FIG. 2 is a perspective view of the portable enclosure with the front flap in a closed position.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a bottom view thereof; and,

FIG. 8 is a top view thereof.

The broken line showing of the electric scooter in the figure depicts environmental subject matter that forms no part of the claimed design.
